UNITED STATES PATENT OFFICE.

JOHN D. SHIVEL, OF PORTER TOWNSHIP, CASS COUNTY, MICHIGAN.

HEN'S NEST.

1,187,187.

Specification of Letters Patent. Patented June 13, 1916.

Application filed June 24, 1915. Serial No. 36,079.

To all whom it may concern:

Be it known that I, JOHN D. SHIVEL, a citizen of the United States, residing in the township of Porter, in the county of Cass and State of Michigan, have invented certain new and useful Improvements in Hens' Nests; and I do declare the following to be a full, clear, and exact description of the invention, such as will enable others skilled in the art to which it appertains, to make and use the same.

This invention relates to improvements in a hen's nest, and one object is to provide a construction arranged to discharge a fresh laid egg from the nest into a separate compartment, and to provide means so that the eggs can be stored in said compartment and removed therefrom when the hen has left the nest.

20 A further object of this invention is to provide a hen's nest of this character which is also adapted for use as a setting nest.

A further object of the invention is to provide a device of this character which is simple and durable in construction, inexpensive to manufacture and one which will be very efficient in operation.

With these and numerous other objects in view my invention consists of the novel features of construction, combination and arrangement of parts which will be herein referred to and more particularly pointed out in the specification and claims.

In the accompanying drawings: Figure 1 is a top plan view of my improved hen's nest; Fig. 2 is a central vertical longitudinal section; Fig. 3 is a plan view showing the nest swung back from the receptacle; Figs. 4, 5 and 6 are a central vertical section, a bottom view, and a top view of the lower portion of the nest showing the disk 13 applied thereto; Fig. 7 is a detail section showing a slightly modified form of disk.

In describing my invention I shall refer 45 to the drawing in which similar reference characters designate corresponding parts throughout the several views and in which the numeral 1 designates a box which is made of any preferred form of wood or metal, and 50 has a circular opening 2 in the top thereof, the other sides of the box being closed. A rubber pad 3 is fastened to the bottom of the box in alinement with the vertical opening 2 in the top thereof.

55 The nest 4 comprises an annular flat sheet metal ring of greater diameter than the

opening 2 in the top of the box adapted to be positioned thereon. A smaller sheet metal ring 7 of less size than the rubber pad 3 in the bottom of the box and disposed in vertical alinement therewith is positioned in said box in a horizontal plane beneath the horizontal plane of the ring 5, and said rings are connected by an annular series of radially arranged arcuate wires 6 formed with horizontally extending extremities secured respectively at their upper and lower ends to the bottom face of the upper ring and the corresponding face of the lower ring. A fabric lining 8 is secured at the top and bottom to the supporting ring 5 and the terminal ring 7 of the nest and provides a covering for the arcuate wires 6. A hinge 9 has one of its members constituted by a projection 9^a formed integrally with the outer edge of the supporting ring 5, said projection being curled upon itself to form a knuckle. The other member of the hinge is secured at 11 to the upper surface of the top of the box 1 adjacent the circular opening therein. A lip 12 is formed integrally with and projects from the circular supporting ring 5 at a point diametrically opposite from the hinge 9, the outer end of said lip being bent upwardly and adapted to form a lifting handle for the said nest as will be hereinafter more fully described.

It will be noted that the nest as above described has a centrally disposed circular opening in the bottom thereof formed by the terminal ring 7, and when it is desired to use this nest as a setting nest a circular flat disk 13 having a staple 14 on its under side is positioned in the nest above the said opening, and is secured therein by the fastening member 16 as clearly shown in Fig. 5 of the drawings.

Secured to the lining of the said nest is a nest egg 17 which is formed of any preferred material such as used in the making 100 of such eggs, the purpose of which is obvious.

In operation when the parts of this device are assembled as shown in Figs. 1 and 2 of the drawing, when an egg is laid in the nest 4, the same will drop through the opening in the bottom thereof upon the rubber pad 3, and then roll off to one side in the box 1. This rubber pad 3 will prevent any breakage of the eggs as they drop from the nest into the box or container.

When it is desired to remove the eggs

- from box, the lip or handle 12 on the supporting ring 5 of the nest 4 is grasped and the nest swung upwardly and outwardly from the aperture 2 in the top of the box in 5 which it is positioned, by action of the hinge 9 which connects the said nest and box. The eggs may then be removed easily from the box and the nest swung back into position for the purpose of its use.
- 10 When it is desired to use this hen's nest as a setting nest the circular flat disk 13 is placed over the opening in the nest 4 and secured thereto by the fastening member 16 as shown in Figs. 4 and 5 of the drawings, 15 whereby the eggs will be prevented from dropping through the nest into the box and will be retained therein during the setting. If preferred, a modified form of disk 13' is used as shown in Fig. 7.
- 20 It will be seen that in the provision of a hen's nest embodying the novel features of construction above set forth, the eggs need not be removed every day, nor can they be eaten or become in any way soiled by the hens, 25 as they are protected while in the box. This nest is handy, clean and attractive and may be easily and simply placed on the floor of a building or fastened to the walls or sides thereof, or in any other convenient place.
- 30 From the foregoing description of my improved device the manner of applying the same to use and the operation thereof will be readily understood and it will be seen that I have provided a simple, inexpensive 35 and efficient means for carrying out the objects of the invention.

I claim as my invention:

1. The combination with a box having a flat horizontal top formed with a circular 40 aperture therethrough, of a flat horizontal ring overlying said top and surrounding the aperture therein, said ring being struck from a single sheet of metal and having at

diametrically opposite points on its outer edge a pair of projections, one of said projections being curled upon itself to form a horizontally disposed hinge knuckle while the outer end of the other projection is bent upwardly and constitutes a handle by means of which the ring may be tilted, a hinge 45 member coöperating with said knuckle and secured to the top of the box, and a nest secured to the ring and depending therefrom through the aforesaid aperture into the box, said nest having in its lower end an opening 50 to allow eggs to pass therefrom into said box.

2. In a hen's nest, the combination with a box having a flat horizontal top formed with a circular aperture therethrough, of a wire nest basket of circular formation inserted in said aperture and having a plurality of vertically extending side wires whose upper ends are bent laterally outward in horizontal directions to form a plurality of basket supports resting on the aforesaid horizontal top, said basket having an opening in its bottom to allow the passage of eggs therefrom into the box, a hinge adapted to connect the basket and the top of the box, said hinge having one of the members secured to the latter, and a flat horizontal ring overlying and secured to the laterally bent upper ends of the aforesaid side wires, said ring carrying the other member of the hinge and at the same time serving to retain said side wires in correctly spaced relation.

In testimony whereof I have hereunto set my hand in presence of two subscribing witnesses.

JOHN D. SHIVEL.
